RECHARGEABLE FLASHLIGHT

Arthur H. Moore, Fairfield, and Joseph G. Bacevius,
Bridgeport, Conn., assignors to The Bridgeport Metal
Goods Manufacturing Company, Bridgeport, Conn., a
corporation of Connecticut

Filed Jan. 15, 1968, Ser. No. 10,153

Term of patent 14 years

U.S. Cl. D48—24
Int. Cl. D26—04

Fig. 1.

Fig. 2.

Fig. 3.

Fig. 4.

Fig. 5.

Fig. 6.

FIG. 1 is a top plan view of a rechargeable flashlight or similar article of and embodying our new design;

FIG. 2 is a rear elevational view thereof;

FIG. 3 is a left side elevational view thereof, the right side elevational view being a mirror image;

FIG. 4 is a front elevational view thereof;

FIG. 5 is a front elevational view thereof taken in a plane parallel to the plane of the face of the flashlight;

FIG. 6 is a bottom plan view thereof.

The characteristic feature of our flashlight resides in the general configuration of the housing as shown.

We claim:

The ornamental design for a rechargeable flashlight, substantially as shown and described.
